UNITED STATES PATENT OFFICE.

ROBERT BROWN, OF GREENVILLE, MISSOURI.

ELECTRIC-DESPATCH SYSTEM.

1,109,397.

Specification of Letters Patent.

Patented Sept. 1, 1914.

Application filed May 3, 1912. Serial No. 695,006.

To all whom it may concern:

Be it known that I, ROBERT BROWN, a citizen of the United States, residing at Greenville, in the county of Wayne and State of Missouri, have invented new and useful Improvements in Electric-Despatch Systems, of which the following is a specification.

The invention is directed to an improvement in electric despatch systems and the general object of the invention is to expedite the transporting of mail from the post-office to the various points of destination on a rural route, and to facilitate and expedite the delivery and collecting of the mail at various points on the said route; and to this end the invention consists in certain improved constructions, arrangements, and combinations of devices, which will be fully described hereinafter, and then pointed out in the claims.

Other objects will appear and be better understood from that embodiment of my invention of which the following is a specification, reference being had to the accompanying drawings forming a part hereof, in which;

Figure 1 is a side elevation of a section of a mail carrying device constructed in accordance with my invention. Fig. 2 is an end view of Fig. 1. Fig. 3 is a detail perspective partly in section of the retarding mechanism. Fig. 4 is a view similar to Fig. 3 of the stopping mechanism.

The elevated track, a section of which is shown in Figs. 1 and 2, is arranged along the mail route and is preferably in the form of a loop whose opposite ends connect to the post-office (not shown).

The poles or uprights 5 are of any suitable construction and length and are arranged at suitable distances apart on the out-going and in-coming sections of the route. The arms 6 which are suitably connected at one end to the upper end portions of the poles 5, are of suitable material such as metal and may be of any convenient length. The brackets 7-7 which depend from and are suitably secured to the arms 6, are of suitable material such as metal, and of any convenient contour such as right angular.

The track rails 8-8 which are suitably connected to the adjacent ends of the brackets 7-7, are of metal and preferably grooved longitudinally in their upper and lower sides as indicated at 9-9.

The car body 10 formed of any suitable material such as metal, is suitably adapted for containing and supporting the electric motor 11, the end portions of whose shaft project beyond the opposite sides of the car body and is provided with wheels 12 which are adapted to be received in the upper grooves 9-9 of the tracks 8-8. The wheels 13 which are on the opposite ends of an axle 14 at that end of the car body remote from the motor 11, and one of which is shown in Fig. 1, are adapted to be received by the grooves 9-9 in the upper sides of the track rails 8-8 and to coöperate with the wheels 12-12 to hold the car body in horizontal position on the track rails 8-8.

The spring pressed trolley pole 15 has at one end a sheave 16 adapted in the ordinary manner for moving on the trolley wire 17 supported from the arms 6, and at its opposite end, is suitably connected to a head 18 which is electrically connected to the motor 11.

The spring pressed lever 19 which is pivoted as at 20 to the side of the car body 10, has at one end portion a recess in which is journaled a shaft 21 upon which is mounted a sheave 22 which is suitably connected such as by a belt 23, to a sheave 24 mounted on an axle 25 at the other end portion of the lever 19 and forming a part of a friction disk 26 which is normally spaced from a friction disk 27 on a shaft 28, journaled in a side of the car body 10. A suitable connection such as by means of bevel gears 29, is established between a shaft 28 and an oblique shaft 30 journaled in a bracket 31 suitably connected to the car body 10.

The sleeve 32 which is loose upon the shaft 30, is moved longitudinally of the shaft by the action of the centrifugal governor 33 and when so moved, a flange or head 34 on the sleeve, which, by preference, is loosely connected to the trolley pole 15, depresses 100 the trolley pole so as to break the electrical connection between the trolley wire 17 and the motor 11.

It may here be stated that the elevation of the track above the ground is greater between points of delivery and discharge where the track is within reaching distance of a person of ordinary height standing on the ground. At such points where the track is lowered, suitable depending extensions 35 are formed with or otherwise suitably connected to one of the track rails 8. The lower

sides of these extensions which may be of any convenient length, incline upwardly from their medial portions and merge into the track rail so as to permit of the easy introduction of the wheel 36 on the shaft 21 to each extension, and the gradual depression and elevation of the lever 19. Thus, when a car moves onto the lowered portion of the track and the wheel 36 thereof moves onto the depending extension 35, the lever 19 will be rocked so as to effect contact between the friction disks 26 and 27. Since the wheel 36 is now rotating owing to the movement of the car, and its frictional contact with the track rail, the sheave 22 which is belted to the sheave 24, will cause the turning of the friction disks and the shaft 30. This movement of the shaft 30 will operate the centrifugal governor which, if the car be traveling above a predetermined rate of speed, will through the sleeve, retract the trolley pole 15 from contact with the trolley wire 17. With the electric connection now broken, the speed of the car will soon be reduced to the required amount and when below this required amount, the spring of the trolley pole will restore the latter to contact with the trolley wire, whereupon the car will gradually attain a predetermined speed and when such speed is exceeded, the trolley pole will be operated as before. This action will continue until the wheel 36 has practically cleared the extension 35.

The carrier 37 which depends from the car body 10 has a plurality of open-ended compartments 38 which correspond in number to the number of stations or places where mail is to be discharged and delivered on the route.

As the car approaches the post-office on its return trip a wheel 52 carried by one end of a lever 53 connected to a shaft 53^a journaled in the car body 10, will move over a depending extension 54 on the track 8 opposite site that upon which the extensions 35 are mounted, the extension 54 projecting farther downward than any of the extensions 35. This will operate to rock the lever 53 and the shaft 53^a and cause one end of a brake 55 connected by a link 56 to the lever,

to frictionally contact with one end of the motor shaft. Simultaneously with the action of the brake, a crank 57 on the shaft 53^a will pull downwardly on an arm 58 to which it is pivotally connected and cause the arm which is secured to the trolley pole 15, to retract the said trolley pole from contact with the trolley wire 17. This will have the effect of breaking the electric connection between the motor and trolley in applying the brake and thereby cause an abrupt stoppage of the car, or substantially so.

What I claim as new is:

1. In an article carrying device, the combination with an elevated track, a trolley car adapted to travel on the track, and a trolley pole carried by the car; of means for retracting the trolley pole from contact with the trolley wire under predetermined conditions (and including an element depending from the track), a centrifugal governor carried by the car and connected to the pole, and means actuated by said element for driving said governors.

2. In an article carrying device, the combination with an elevated track, and a trolley car adapted to travel on the track; of means for retarding the speed of the car under predetermined conditions, said means including a rocking element adapted for engagement with said track, a centrifugal governor adapted to retract the trolley pole intermittently from the trolley wire, and means for driving said governor.

3. In an article carrying device, the combination with an elevated track, a trolley car adapted to travel on said track, a trolley wire, and a trolley pole carried by the car, of means for retracting the pole from contact with the trolley wire under predetermined conditions, said means including a governor carried by the car and connected to the pole, and means connected to said car for driving said governor.

In testimony whereof I affix my signature in presence of two witnesses.

ROBERT BROWN.
